United States Patent Office

Des. 178,565
Patented Aug. 21, 1956

178,565

HANDLE

Earl R. Heavner, Dayton, Ohio

Application July 13, 1955, Serial No. 36,958

Term of patent 14 years

(Cl. D9—1)

FIG. 1

FIG. 2

FIG. 3

FIG. 4

I claim:

The ornamental design for a handle, as shown.
